UNITED STATES PATENT OFFICE

LOUIS F. SCHLENKER AND MARTIN WUERTHNER, OF JACKSON, MICHIGAN, ASSIGNEES
TO SAID SCHLENKER AND SAID WUERTHNER, AS JOINT TENANTS WITH RIGHT OF
SURVIVORSHIP

COMBINED HEATING AND VENTILATING APPARATUS

Application filed October 21, 1929. Serial No. 401,328.

The invention relates to combined heating and ventilating apparatus.

The object of the present invention is to provide a simple, practical and efficient combined heating and ventilating apparatus of comparatively inexpensive construction designed for heating and ventilating residences, apartments, hospitals, and other buildings, and equipped with means, in the event of a fire, of exhausting and removing from the rooms smoke and gases, to enable occupants to escape more readily and without danger of being overcome by smoke and fumes, and at the same time afford a clear and positive indication of the location of the fire to enable the means for extinguishing the same to be localized and rendered more effective than is the case where the particular point of conflagration is in doubt.

A further object of the invention is to provide a combined heating and ventilating device of this character which will be particularly effective for use in hospitals and other places where a constant supply of fresh air is essential, and where a moderate heating is necessary or desirable.

With these and other objects in view, the invention consists in the construction and novel arrangement and combination of parts hereinafter described, illustrated in the accompanying drawings, and set forth in the claims hereto appended, it being understood that various changes in the form, proportion, and minor details of construction, within the scope of the claims, may be resorted to without departing from the spirit of the invention or sacrificing any of the advantages thereof.

In the drawings:

Fig. 1 is a vertical sectional view of a building equipped with a combined heating and ventilating apparatus constructed in accordance with this invention.

Fig. 2 is an enlarged side elevation, partly in section, illustrating more clearly the details of the apparatus.

Fig. 2 is an enlarged side elevation, partly construction of the distributing ducts of the main supply pipe.

Fig. 4 is a detail vertical sectional view of

one of the branches of the distributing ducts, illustrating the construction of the radiator.

Fig. 5 is a horizontal sectional view of the insulated air-tight air chamber.

In the accompanying drawings, in which is illustrated the preferred embodiment of the invention, the combined heating and ventilating apparatus comprises in its construction an insulated air-tight air chamber 1 designed to be constructed of any suitable material and equipped at one of its sides with a door 2 to afford access to its interior and designed to be interiorly located or mounted in or at the lower portion of a building 3, as clearly illustrated in Fig. 1 of the drawings. The building may be a residence, apartment, hospital, or any other structure of a similar character where a heating and ventilating apparatus is desirable.

Cold air from the exterior of the building is supplied to the air chamber 1 by means of a cold air inlet-pipe or conduit 4, preferably arranged vertically, as illustrated in Fig. 1 of the drawings, and extending upwardly from the air chamber through the roof to the exterior of the building, or as otherwise expressed, inwardly or downwardly from the exterior of the building to the air chamber. The pipe or conduit 4 is provided at its upper end with an elbow 5 forming a horizontally disposed inlet for the cold air, but any other suitable type of inlet may, of course, be employed, as will be readily understood. The cold air intake conduit extends downwardly through the top of the air chamber to within a short distance of the bottom thereof, and is preferably provided with an enlarged lower inner or delivery end 6, forming a hood or cap which is located above and is spaced in relation to electric heaters 7 of any desired construction. The cold air descending through the inlet conduit 4 is heated by the electric heater and is conducted from the air chamber through a main supply pipe 8 to the various rooms 9 of the building when it is desired to heat the latter.

The heating feature of the apparatus is designed for use in the spring and fall of the year, when it is not desirable to start a furnace and when the weather is such that a

limited amount of heat is necessary to render the rooms comfortable. In practice, any suitable switch mechanism may be employed for starting the electric heater, and such switches 5 may be arranged both at a central point and at the various rooms and apartments. When the heating of the building is not required, the main supply pipe is employed for distributing fresh air to the various rooms for 10 ventilation.

The main supply pipe 8 is illustrated in the drawings extending downwardly from the center of a space enclosed by the electric heater, being provided with a short vertical 15 portion 10 and a short horizontal portion 11, which connects the main vertical portion of the supply pipe with the air chamber. Instead, however, of conducting the hot air from the air chamber at the bottom thereof 20 as shown, any other desired arrangement of the intake or inlet conduit and the main supply pipe may be employed, and the latter may be connected at any other desired point with the air chamber, for instance, at the top 25 thereof, and the position of the electric heater may be changed to arrange it directly beneath the supply pipe. The vertical body portion of the main supply pipe communicates with and is connected to the inner ends of horizontal distributing ducts 12 extending across the various rooms 9 and preferably arranged in the walls thereof and provided at intervals 30 with branches 13 extending in opposite directions and arranged at right angles to the distributing ducts and provided at their outer ends with tapered or funnel shaped portions 14 located at the faces of the walls of the 35 various rooms.

The funnel shaped portions 14 are provided with registers 15 of the ordinary construction and adapted to be operated in the usual manner to open and close the branches. The registers are adapted to be opened and closed, and any desired number may be provided for a room, so as to afford the desired 45 amount of heat or ventilation.

The distributing ducts are provided with outer terminal portions 16 extending through the walls of the building to the exterior 50 thereof and controlled by suitable dampers 17 which are adapted to be opened for enabling smoke, dust, fumes, and the like to be exhausted from the various rooms and discharged exteriorly of the building, as hereinafter more fully explained. Means are provided, as hereinafter explained, for creating a suction at the registers and in the branches of the distributing ducts and exhausting smoke and fumes from a fire and 55 discharging them through the terminal portions of the distributing ducts so as to clear the rooms of smoke in the event of a fire, and thereby enable the occupants to escape more readily and also to combat and extinguish the 60 fire more quickly and effectively than when

the rooms are filled with smoke and gas masks are necessary. The dampers 17 are normally closed to prevent loss of heat through the terminal extensions of the distributing ducts, and in practice any suitable 70 means may be employed for operating the dampers.

The combined ventilating and heating apparatus is equipped with a blower 18 designed to be electrically operated and controlled by a suitable switch or switches and having an intake pipe 19 extending through the wall of the building to the exterior thereof as indicated in Fig. 1 of the drawings. The blower may be of any desired construction, and, as the particular construction thereof does not constitute a portion of the present invention, a further description thereof is deemed unnecessary, as various types of blowers may be employed. The discharge pipe 20 of the blower is connected with an air intake blower pipe 21, a blower exhausting pipe 22, and a blower circulating pipe 23, which are individually controlled by valves 24, 25 and 26. 80

The blower pipe 21 extends to the horizontal inlet of the air intake conduit 4 and is provided with a nozzle 27 discharging into the cold air intake. The said blower pipe 21 is also provided with a branch 28 connected with the pipe 21 a short distance below the nozzle 27 and extending interiorly of and down the cold air intake conduit to within a short distance of the lower end thereof and having its lower end or nozzle 29 located a short distance above the electric heater and above the inner end of the main supply pipe. When the valve 24 is open, the air from the blower will be discharged into the inlet end of the cold air intake and also at the lower end thereof. This will cause the cold or fresh air either for ventilating or heating purposes to flow downward through the conduit 4 into contact with the electric heaters, and will prevent the heated air from rising and escaping through the conduit 4, so that there will be no loss of heated air through the said conduit 4. 100

The blower pipe 23 extends into the air chamber and is provided with a depending downwardly discharging nozzle 30 located at the inner end of the main supply pipe and discharging into the same. When the valve 26 is opened the air discharging from the nozzle 30 will induce the heated air to flow through the main air supply pipe and will overcome the natural draft through the said pipe and cause the heated air to be carried by the main air supply pipe to the distributing ducts so as to be discharged at the registers in the various rooms of the building. The valves 24 and 26 are always open when the apparatus is used for either heating or ventilating purposes, and the amount of cold or fresh air admitted to the air chamber is controlled by a suitable damper 31 located within the cold air 110 120 125 130

conduit 4 and preferably arranged a short distance above the air chamber, as clearly illustrated in Figs. 1 and 2 of the drawings.

Any suitable means may, of course, be employed for operating the damper, and any suitable form of damper may be provided. Also, when the apparatus is employed for heating and ventilating purposes, the dampers 17 at the outer ends of the distributing ducts will be closed, so that all of the air carried by the main air supply pipes will be discharged into the various rooms of the building and not escape to the exterior thereof through the outer ends of the distributing ducts.

The blower pipe 22 extends to points adjacent the distributing ducts and is provided with branch pipes 32 extending along the distributing ducts and provided with 20 branches 33 arranged adjacent to and extending along the branches of the distributing ducts to the radiators thereof. The branches 33 are provided at their outer ends with reversely arranged nozzles 34 extending 25 into the tapered or funnel shaped portions of the branches 13 and projecting into the said branches 13, as clearly illustrated in Fig. 4 of the drawings, so as to direct currents of air backwardly through the said branches 13.

30 This will produce a suction effect in the registers for drawing off smoke, fumes and other impurities. When the valve 25 is opened the dampers 17 are also opened, so that the air passing upward in the main supply pipe and outwardly through the horizontal distributing ducts will be discharged from the outer ends of the said distributing ducts and with the aid of the reversely arranged nozzles 34 draw off and exhaust the smoke, fumes and 40 the like from the rooms. Should a fire occur in any portion of a building equipped with the combined heating and ventilating apparatus, and the same be arranged for exhausting smoke from the rooms, any room containing smoke will have the same cleared and exhausted through its registers and discharged at the outer end of the distributing duct having such registers, and the discharge 50 of smoke from such distributing duct will indicate clearly and positively the location of the fire. Also, the removal of smoke and fumes will greatly assist in the escape of the occupants and at the same time render the 55 means for fighting a blaze and extinguishing a fire more effective in enabling the same to be localized and in permitting firemen and other persons to fight such fire without the necessity of gas masks.

60 Instead of operating the blower electrically, any other suitable means, such as compressed air or steam, may, of course, be employed, and any suitable type of heater may also be provided, but an electrically operated and controlled blower, and an elec-

trically operated and controlled heater, will be found particularly advantageous.

What is claimed is:

1. A heating and ventilating apparatus comprising in combination an air chamber, means associated therewith which can be employed for heating air passing into and through said chamber, a cold air intake pipe connected with and leading to said air chamber, a main supply pipe connected with and leading from said air chamber, a distributing duct connected with and leading from the main supply pipe, a damper in the outer terminal portion of the distributing duct, branch ducts connected to said distributing duct, each branch duct being provided with a register, a blower, valve-controlled air intake blow piping connecting with and leading from the discharge duct of the blower to the cold air intake pipe for forcing air through the intake pipe thence into the air chamber when the valve-controlled air intake blow piping is open, valve-controlled blower-circulating piping connected with and leading from the discharge duct of the blower to the main supply pipe for forcing air from the chamber into, along and through the main supply pipe when the valve-controlled blower-circulating piping is open, and valve-controlled blower exhausting piping connected with and leading from the discharge duct of the blower to the branch ducts for the purpose of forcing air into the branch ducts and thence into the distributing duct when the valve-controlled blower exhausting piping is open. 70 75 80 85 90 95 100

2. A heating and ventilating apparatus comprising in combination an air chamber, means associated therewith which can be employed for heating air passing into and through said chamber, a cold air intake pipe connected with and leading to said air chamber, a main supply pipe connected with and leading from said air chamber, a distributing duct connected with the leading from the main supply pipe, a damper in the outer terminal portion of the distributing duct, branch ducts connected to said distributing duct, each branch duct being provided with a register, a blower, valve-controlled piping connected with and leading from the discharge duct of the blower and arranged for causing air to pass inwardly into and through the cold air intake pipe, thence into the air chamber and therefrom into and through the main supply pipe when said valve-controlled piping is open, and valve-controlled blower exhausting piping connected with and leading from the discharge duct of the blower to the branch ducts for the purpose of forcing air into the branch ducts and thence into the distributing duct when the valve-controlled blower exhausting piping is open. 105 110 115 120 125

3. An apparatus used in connection with a building having a plurality of rooms, which 130

- apparatus includes in combination an interiorly located air chamber, a cold air intake conduit communicating with the said chamber and extending to the exterior of the building, a main supply pipe extending from the said chamber for distributing air therefrom to the rooms of the building, a blower, and separate independently controlled discharge pipes leading from the blower and provided with nozzles discharging respectively into the outer end of the intake conduit and into the inner end of the main supply pipe to create a suction through said conduit and the supply pipe.
4. In combination with a building having rooms, an apparatus including an air chamber located at the bottom of the building, a cold air intake conduit communicating with the said chamber and extending to the exterior of the building, a main supply pipe extending from the said chamber for distributing air therefrom to the rooms of the building, a blower, and separate independently controlled discharge pipes leading from the blower and provided with nozzles discharging respectively into the outer end of the intake conduit and the inner end of the main supply pipe, one of the said discharge pipes having a branch extending downwardly through the intake conduit and provided adjacent the lower end thereof with a nozzle directed towards the said lower end of the intake conduit to increase the suction through the cold air conduit.
5. An apparatus of the class described used in connection with a building having a plurality of rooms, which apparatus includes in combination an air chamber located at the bottom of the building, a cold air intake conduit extending through the top of the said chamber and extending through the top of the building, a main supply pipe extending from the said chamber to distribute air to the rooms of the building and located directly beneath the lower end of the intake conduit, a blower, and separate independently controlled discharge pipes leading from the blower, one of the discharge pipes extending to the cold air intake and having a nozzle discharging into the same and provided also with a branch pipe extending into and along the intake conduit to the lower portion thereof and provided thereat with a discharge nozzle to create a suction through said conduit, the other discharge pipe extending to the inner end of the main supply pipe and provided with a nozzle discharging into the same to force the air through the main air supply pipe.
6. A heating and ventilating apparatus for use in conjunction with buildings having a plurality of rooms, said apparatus including in combination an interiorly located air chamber, a cold air intake conduit communicating with the air chamber for supplying
- cold air to the same and extending from the air chamber to the exterior of the building, a main supply pipe connected with the air chamber for distributing air to the rooms of the building, a heater within the said chamber, a blower, and separate independently controlled discharge pipes extending from the blower to the cold air intake conduit and to the main supply pipe and provided with nozzles discharging into the same for forcing the cold air through the conduit and heated air through the main supply pipe.
7. In a building having a plurality of rooms an apparatus which includes in combination an interiorly located air chamber, a cold air intake conduit communicating with the air chamber for supplying cold air to the same and extending therefrom to the exterior of the building, a main supply pipe connected with the air chamber for conveying air to the rooms of the building, a heater within the said chamber, a blower, and separate independently controlled discharge pipes extending from the blower to the cold air intake conduit and to the main supply pipe and provided with nozzles discharging into the same and arranged to force cold air through said conduit and heated air through the main supply pipe, said cold air intake conduit being located directly above the inner end of the main supply pipe and the heater being interposed between the cold air intake conduit and the supply pipe.
8. A heating and ventilating apparatus used in a building having a plurality of rooms, which apparatus includes in combination an air chamber located at the bottom of the building, a cold air intake conduit communicating with the air chamber for supplying cold air to the same and extending from the air chamber to the exterior of the building, a main supply pipe connected with the air chamber, a heater within the said chamber, a blower, and separate independently controlled discharge pipes extending from the blower to the cold air intake conduit and to the main supply pipe and provided with nozzles discharging into the outer end of the said conduit and into the inner end of the main supply pipe for forcing cold air through the conduit and heated air through the main supply pipe, said cold air intake conduit being provided at its inner end with an enlarged portion for hood arranged over the heater.
9. An apparatus of the class described, used in connection with a building having a plurality of rooms, which apparatus includes in combination an air chamber located at the bottom of the building, a cold air intake conduit communicating with the air chamber for supplying cold air to the same and extending downwardly from the exterior of the building to the air chamber, a main supply pipe connected with the air

- chamber for delivering air to the rooms of the building; an electric heater within the said chamber, a blower, and separate independently controlled discharge pipes extending from the blower to the cold air intake conduit and to the main supply pipe and provided with nozzles discharging into the upper end of said conduit and the inner end of the main supply pipe for forcing cold air through the conduit and heated air through the main supply pipe the delivery end of, said cold air intake conduit being located directly above the inner end of the main supply pipe, the heater being interposed between the cold air intake conduit and the supply pipe, and the cold air intake conduit being provided with an enlarged delivery end forming a hood for the heater.
10. An apparatus used in connection with a building having rooms, which apparatus includes an air chamber located at the bottom of the building, a cold air intake conduit communicating with the air chamber and extending to the top of the building, a main supply pipe extending from the air chamber and provided with distributing ducts having branches provided with registers and which branches extend to the rooms of the building, a blower, and separate independently controlled discharge pipes leading from the blower and provided with nozzles located at and discharging into the cold air intake conduit and the main supply pipe and arranged to force cold air through the air intake conduit into the air chamber and air from the air chamber outwardly through the main supply pipe.
11. In a building having rooms, an apparatus including in combination an air chamber, a cold air intake conduit communicating with the air chamber and extending to the exterior of the building, a main supply pipe extending from the air chamber and provided with distributing ducts having branches provided with registers located in the rooms of the building, a blower, and separate independently controlled discharge pipes leading from the blower and provided with nozzles located at and discharging into the cold air intake and the main supply pipe and arranged to force cold air through the intake conduit into the air chamber and therefrom outwardly through the main supply pipe, said blower being also provided with a discharge pipe leading therefrom and extending to the said registers and having reversely arranged nozzles discharging into the branch pipes of the distributing ducts for forcing smoke gas and foul air from the rooms into the registers.
12. In a building having rooms, an apparatus which includes in combination an air chamber located at the bottom of the building, a cold air intake conduit communicating with the air chamber and extending to the
- exterior of the building, a main supply pipe extending from the air chamber and provided with distributing ducts having branches provided with registers for the rooms of the building, a blower, separate independently controlled discharge pipes leading from the blower and provided with nozzles located at and discharging into the cold air intake and the main supply pipe for forcing air through the same, said blower being also provided with a discharge pipe leading therefrom and extending to the said registers and having reversely arranged nozzles discharging into the branch pipes of the distributing ducts for forcing smoke, gases and foul air from the rooms into the distributing ducts, and means for connecting the distributing ducts with the outside atmosphere.
13. An apparatus of the class described, used in connection with a building having a plurality of rooms, which apparatus includes in combination an interiorly located air chamber, a cold air intake conduit communicating with the air chamber and extending to the exterior of the building, a main supply pipe extending from the air chamber and provided with distributing ducts having branches provided with registers located in the rooms of the building, a blower, separate independently controlled discharge pipes leading from the blower and provided with nozzles located at and discharging into the cold air intake and the main supply pipe, said blower being also provided with a discharge pipe leading therefrom and extending to the said registers and having reversely arranged nozzles discharging into the branch pipes of the distributing ducts for forcing smoke, gases, and foul air from the rooms into the registers, damper controlled means for connecting the distributing ducts with the outside atmosphere, and a heater arranged within the air chamber and interposed between the cold air intake conduit and the main supply pipe.
14. In a building having rooms, an apparatus including in combination an air chamber located at the bottom of the building, a cold air intake conduit connected with the air chamber and extending to the exterior of the building, a main supply pipe extending from the air chamber and provided with distributing ducts having branches extending to the rooms of the building and provided with enlarged terminal portions having registers, heating means arranged within the air chamber, a blower, separate independently controlled discharge pipes leading from the blower and provided with nozzles discharging into the cold air intake conduit and the main supply pipe, said blower being also provided with a separate independently controlled discharge pipe leading therefrom and extending to the registers and provided with nozzles discharging into the same for forcing

smoke, gases and foul air from the rooms into the registers, and a damper located in the cold air intake conduit for closing the same when the blower is operating to suck smoke, gases and the like from the rooms into the registers.

In testimony whereof we have hereunto signed our names, this 18th day of October, 1929.
